Specification for Design.

Patented Mar. 12, 1918.

Application filed April 12, 1917. Serial No. 161,662. Term of patent 14 years.

To all whom it may concern:

Be it known that I, ROBERT M. PIERSON, a citizen of the United States, residing at Akron, in the county of Summit and State of Ohio, have invented a new, original, and ornamental Design for Pneumatic Tires, of which the following is a specification, reference being had to the accompanying drawings, forming a part thereof.

Figure 1 represents a plan view of a pneu-

matic tire extended or flattened out and bearing my new design.

Fig. 2 represents a cross section of the outer half of a tire wall in its normal shape, taken on the line 2—2 of Fig. 1.

I claim:

The ornamental design for a pneumatic tire as shown.

ROBERT M. PIERSON.
